UNITED STATES PATENT OFFICE.

GUSS C. SALLEY, OF MANHATTAN, KANSAS.

HEMOSTATIC INSTRUMENT.

Application filed April 25, 1928. Serial No. 272,760.

My invention relates to improvements in hemostatic instruments.

The object of my invention is to provide a novel hemostatic instrument, which is simple, cheap, durable, not likely to get out of order, which can be very quickly applied and released, and with which an arm or leg of a person may be held tightly compressed, for the purpose of arresting a hemorrhage therefrom, or to check the return flow of the blood through the venous system without materially checking the arterial flow, whereby the veins will be enlarged enabling the easy introduction therewith of a hypodermic needle or trocar for the administration directly into the blood stream of medicines, serums, vaccines, etc.

The novel features of my invention are hereinafter fully described and claimed.

In the accompanying drawing, which illustrates the preferred embodiment of my invention.

Fig. 1 is a plan view of the instrument, partly broken away, looking at one side thereof, with the jaws open and handles released.

Fig. 2 is a similar view, looking at the other side of the instrument, the handles being locked and the jaws closed and holding the rubber tube clamped between them.

Fig. 3 is an end view of what is shown in Fig. 2.

Similar characters of reference designate similar parts in the different views.

My improved instrument may embody the usual type of hemostat having two members 1 and 2 respectively provided with jaws 3 and 4, and handles 5 and 6. The handle 6 has a lateral extension 7 having a tooth 8 adapted to releasably engage teeth 9 of a lateral projection 10 on the handle 5. The members 1 and 2 are pivotally connected, after the manner of shears, by a screw 11.

A compressing member, which is flexible, and, preferably, resilient, such as a rubber tube 12 is fastened at one end to the jaw 3. Such fastening means for the tube 12 consists in fitting one end of the tube on the jaw 3 and having the tube extend past the screw 11 onto the handle 5, the screw 11 being removed together with the member 2, for this purpose.

The tube 12 has in one side a notch 13 which is adapted to receive the member 2 and which permits the latter to swing on the screw 11. After the tube 12 is fitted

on the member 1, the member 2 is replaced and fastened to the member 1 by the screw 11.

In the operation of the invention, the jaws 3 and 4 are opened, and the tube is wound tightly around the arm or leg to be compressed and the tube then inserted between the jaws 3 and 4, the handles 5 and 6 being then forced toward each other and the tooth 8 engaged with one of the teeth 9, thus releasably securely holding the jaws 3 and 4 tightly clamping the tightly drawn tube 12 and forming a tourniquet of the latter.

When it is desired to remove the tourniquet, the handles 5 and 6 are released from each other, upon which the tube 12 will be released from the jaws 3 and 4.

The arrangement is such that the instrument is easily operable, and after being applied to the limb, it will securely hold the same compressed without the attention thereafter of the operator and without danger of accidentally being released.

I do not limit my invention to the structure shown and described, as many modifications, within the scope of the appended claims, may be made without departing from the spirit of my invention.

What I claim is:—

1. In a hemostatic instrument, the combination with two members pivoted to each other and having cooperating jaws and handles and provided with means for releasably locking the handles to hold the jaws in a clamping position, of a flexible member attached to one of said jaws and adapted to encircle and compress a portion of a person's body and to be held releasably clamped between said jaws.

2. In a hemostatic instrument, the combination with two members pivoted to each other and having cooperating jaws and handles and provided with means for releasably locking the handles to hold the jaws in a clamping position, of a resilient member attached to one of said jaws and adapted to encircle and compress a portion of a person's body and adapted to be held releasably clamped between said jaws.

3. In a hemostatic instrument, the combination with two members pivoted to each other and having cooperating jaws and handles and provided with means for releasably locking the handles to hold the jaws in a clamping position, of a rubber

tube fastened to and fitted at one end on one of said jaws and adapted to encircle and compress a portion of a person's body and adapted to be held clamped releasably between said jaws.

4. In a hemostatic instrument, the combination with two members pivoted to each other and having cooperating jaws and handles and provided with means for releasably locking the handles to hold the

jaws in a clamping position, of a rubber tube having one end fitted on the jaw of one of said members and extending past the pivotal point and onto the handle thereof, and having a lateral notch in which the other member is disposed.

In testimony whereof I have signed my name to this specification.

GUSS C. SALLEY.
